UNITED STATES PATENT OFFICE

2,056,033

ELECTRIC CIRCUIT INTERRUPTER

Josef Biermanns, Berlin-Johannisthal, Germany,
assignor to General Electric Company, a corporation of New York

Application December 5, 1935, Serial No. 53,074
In Germany December 15, 1934

3 Claims. (Cl. 200—148)

My invention relates to electric circuit interrupters, more particularly to those of the fluid-blast type wherein the arc drawn upon opening of the circuit is subjected to an extinguishing jet or blast of fluid, and has for its principal object the provision of an improved circuit interrupter of the aforesaid type which shall be uniformly effective over a comparatively wide interrupting range.

My invention will be more fully set forth in the following description referring to the accompanying drawing, and the features of novelty which characterize my invention will be pointed out with particularity in the claims annexed to and forming a part of this specification.

15 Referring to the drawing, the single figure thereof is an elevational view, partly in section, of an electric circuit interrupter comprising my invention in the closed circuit position.

The electric circuit interrupter illustrated, by way of example, comprises a base structure 1 on which are mounted the relatively movable contacts, comprising in the present instance a fixed socket-type contact 2 of well-known construction and a coacting movable rod contact 3. The contacts which are shown in the closed circuit position engage by reason of a garter spring 4 which presses a plurality of segmental contacts into engagement with the rod contact 3.

30 The fixed contact 2 is mounted within a casing 5 defining a pressure-confining arc chamber, the casing 5 in the present instance being of conducting material and serving as one terminal of the circuit interrupter. The fixed contact 2 is resiliently mounted within the casing 5 by means of the spring 6.

The casing 5 is provided with an exhaust passage comprising, in the present instance, a comparatively long tubular member 7 of insulating material suitably secured to the casing 5. The rod contact 3 is guided within the tube 7 and forms a fairly close fit with the tube so that exhaust from the arc chamber is to a great extent precluded as long as the rod contact 3 is in the exhaust passage.

45 The operating means for the rod contact comprises an insulator 8 pivotally mounted at 9 on the base and connected at its upper bifurcated end 8' to a forked member 10, which is in turn connected at 11 to an extension 12 of the rod contact. The extension 12 is slidably guided at 13' in the other terminal structure 13. Accordingly, an operating force suitably applied to the shaft 9 for rocking the insulator 8 is effective to move the rod contact 3 into or out of engagement with the coacting fixed contact 2, the contact 3 in the open

circuit position being exteriorly of the tube 7 so that arcing pressure within the casing 5 is suddenly released to cause a fluid blast through the arc between the contacts 2 and 3. The terminal casing 5 and the terminal structure at 13 are each suitably supported on the base 1 by insulators 14 and 15, respectively.

In the arrangement so far described, wherein the chamber in which the fixed contact is disposed is filled with air and merges into an insulating tube closely surrounding the contact rod, the arc created upon opening of the circuit forms a more or less high pressure, either by heating the air in the arc chamber or by the evaporation of the insulating material with which the arc comes in contact. The amount of the pressure created is of considerable importance for proper interruption of the arc. In order, therefore, to interrupt comparatively low currents with certainty, it has been proposed to us a comparatively small switch rod operating within as restricted a space as possible. Adequate pressure at comparatively low currents may in such a case be generated. However, in this case the arrangement could not be used for high currents which require a switch rod of much larger diameter, since, if the diameter of the rod is increased, the interruption of the arc at low currents will not be satisfactory or uniform by reason of the increased volume of the arcing space.

35 In accordance with my invention, the circuit interrupter is provided with a source of auxiliary fluid pressure which is effective at low currents for augmenting or supplanting the arc pressure in the arc chamber and which at high currents does not affect the arc pressure. With this arrangement the interrupting capacity of the switch does not depend on the volume of the current interrupted.

The source of auxiliary fluid pressure may constitute, in the case of a gas-blast switch, a separate source of compressed gas, using, for example, for this purpose the compressed gas necessary for the corresponding gas-operated switch mechanism, or the compressed gas may be produced by the switching operation itself.

To this end, the contact operating insulator 8 is connected at 16 through a piston rod 17 to a piston 18, the piston operating within a cylinder 19 which is arranged to be in communication, through the conduit 20, with the arc chamber in the casing 5. A valve 21 is disposed in the casing 5 for controlling the passage through the conduit 20 and is biased by a light spring 22 into seating engagement so as normally to close said passage,

the valve being seated so as to be opened by pressure within the conduit 20.

Accordingly, at low currents the compressed gas supplied by the piston 18 increases the pressure within the arc chamber so that the arc is effectively interrupted when the rod 3 leaves the tube 1, whereas at high currents the arc itself produces sufficiently large pressure for interrupting the circuit. In the case of low currents, the valve 21 admits, without appreciable resistance, gas under pressure to the arc chamber and at some predetermined higher current the arcing pressure within the chamber is greater than the pressure developed by the piston 18, with the result that the valve 21 is closed and the exhaust from the arcing chamber is confined to the insulating tube 1. The valve 21, therefore, not only serves to maintain proper blast pressure within the arc chamber at higher currents, but also prevents the arcing pressure from acting on the piston 18 and momentarily reclosing the switch.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States is:

- 30 1. An electric circuit interrupter of the fluid-blast type comprising relatively movable contacts, one of said contacts being disposed within a pressure-confining arc chamber and another of said contacts being movable from said chamber, arc pressure generated in said chamber causing a fluid blast in the direction of said movable contact, an auxiliary source of fluid pressure arranged to be in communication with said chamber, and a valve between said chamber and source ar-

ranged to close when the arc pressure in said interrupting chamber exceeds that of said source.

2. An electric circuit interrupter of the fluid-blast type comprising relatively movable contacts, one of said contacts being disposed within a pressure-confining arc chamber, said chamber having an exhaust passage defined by a comparatively long tubular member of insulating material, another of said contacts comprising a movable rod for engaging the aforesaid contact in said chamber, said rod being closely surrounded by said insulating tube and movable to an open circuit position exteriorly of said tube, an auxiliary source of fluid pressure arranged to be in communication with said chamber for supplying pressure to said chamber at low currents, and a valve disposed in said chamber controlling communication between said chamber and source arranged to close when the arc pressure in said chamber exceeds the pressure of said source.

3. An electric circuit interrupter of the fluid-blast type comprising relatively movable contacts, one of said contacts being disposed within a pressure-confining arc chamber, said chamber having an exhaust passage defined by an insulating tube, another of said contacts comprising a movable rod slideable through said tube for engaging the aforesaid contact in said chamber, said rod having a comparatively close fit in said tube and movable to an open circuit position exteriorly thereof, a source of pressure arranged to communicate with said chamber including a piston operatively connected to said movable rod contact, said piston supplying auxiliary pressure to said chamber at low currents, and a valve positioned between said chamber and piston arranged to close when the arc pressure in said chamber exceeds the pressure produced by said piston.

JOSEF BIERMANNNS.
